ATTORNEY

UNITED STATES PATENT OFFICE.

JOSEPH BURGER, OF BROOKLYN, NEW YORK.

HEEL.

1,387,639.

Specification of Letters Patent. Patented Apr. 20, 1920.

Application filed July 24, 1919. Serial No. 312,997.

To all whom it may concern:

Be it known that I, JOSEPH BURGER, a citizen of the United States of America, and a resident of Brooklyn, county of Kings, and 5 State of New York, have invented certain new and useful Improvements in Heels, of which the following is a specification, reference being had to the accompanying drawing, forming a part thereof.

10 My invention relates particularly to high heels of the so-called "French" type.

These heels are usually constructed of wood. This material while generally satisfactory is subject to cracking and breaking 15 and particularly at the reduced and weakened neck or "waist" portion of the heel.

One of the principal objects of this invention is to overcome this weakness. This 20 object I have accomplished by reinforcing the heel with dowels driven into the body of the heel from one end thereof. These dowels are preferably constructed of a material having the characteristics of aluminum, which is both light and strong and 25 which is relatively soft and ductile, so as not to interfere with such fastenings as are ordinarily used for applying the top lift of the heel. These dowels also are usually constructed 30 angular or otherwise shaped in cross-section to provide relatively sharp corners or edges and for the sake of greater lightness and strength may be made in tubular form. Another feature is the provision 35 of the dowels with screw threads to cause them to turn into the body of the heel and thus bind the material together.

The foregoing and other features of the invention will appear more fully as the 40 specification proceeds.

The drawing illustrates the invention embodied in a practical and preferred form, but I would have it understood that the construction may be modified to suit various 45 requirements without departure from the true spirit and scope of the invention, as defined in the appended claims.

In said drawing,

Figure 1 is a vertical sectional view of the 50 heel taken substantially on the plane of line 1-1 of Fig. 2.

Fig. 2 is a transverse sectional view taken substantially on the plane of line 2-2 of Fig. 1.

Fig. 3 is a horizontal sectional view on 55 substantially the plane of line 3-3 of Fig. 2.

Fig. 4 is an enlarged side view of one of the dowels and

Fig. 5 is a cross-section on line 5-5 of Fig. 4.

5 designates a heel body of the typical full Louis type, constructed of wood and having the usual reduced and weakened neck or waist portion 6. This reduced neck portion is reinforced, according to the present disclosure by a pair of dowels 7 driven up into the body of the heel from the lower end thereof, said dowels being shown as disposed on opposite sides of the transverse center line of the heel (Fig. 2) and as extending well up into the body of the heel, above the weakened neck portion thereof.

These dowels are preferably constructed of aluminum or material having similar characteristics and are also preferably made 75 tubular in form and angular or otherwise shaped in cross-section to provide the relatively sharp corners or edges, such as indicated at 8 in Fig. 3.

Also, in the present preferred construction the dowels are formed with an external screw thread, such as indicated at 12. This screw thread causes the dowels to "bite" into the material of the heel and to turn as they are being driven, causing the dowels 85 to thereby "bind" the material together. As a result, in case of breakage of the heel, the parts will be held firmly together and the fracture will remain practically imperceptible.

90 In practice, usually a pair of holes of the requisite depth are first bored in the bottom of the heel block, after the block comes from the turning machine and before the end of the block is squared off. The 95 dowels are then driven into the block, turning into the material as they enter, after which the lower end of the block is squared off as by means of the usual saw. The 100 dowels, being preferably constructed of a relatively soft material, such as aluminum, and also being preferably hollow, do not interfere with this cutting off of the heel block, the saw cutting through the dowels practically as easily as the wood and leaving the ends of the dowels flush with the bottom surface of the heel.

105 After being thus reinforced, the top lift

9 may be applied in the usual way, such as by means of the brads 10 and the usual center screw 11, which, as indicated in Figs. 2 and 3 enters into the bottom of the heel between the dowels. These fastenings are usually driven so as to avoid contact with the dowels, but no harm results if these fastenings should come into engagement with the dowels because of the fact that said dowels are of relatively soft material and tubular construction so as to give and yield more or less to such driven fastenings. As an instance, the screw in case it engages the outside or inside of the dowel may cut its seat directly in the metal of the dowel.

I have found by experience that this invention very materially strengthens the wood heel and practically prevents breakage and this without appreciably adding to the weight of the heel or increasing the expense. In tests which I have made where I have purposely fractured the weakened neck portion of the heel, the parts were still held closely together by the dowels and the heel for all practical purposes remained as serviceable as ever. In case of fracture the two dowels serve to prevent relative rotation or twisting of the parts. The dowels themselves by reason of their angular cross-section and relatively sharp corners or edges also individually resist any such twisting strains. A simple and inexpensive method of making the dowels is to cut them in suitable lengths from rods or tubing of the proper size which have been previously formed with screw threads of a suitable pitch. It is possible to thus cut the dowels from continuous lengths of rod or tubing

because of the fact that the dowels require no "pointing" and can be used with square ends, such as disclosed.

What I claim is:

1. The combination with a one-piece turned wooden heel, of a pair of dowels driven from the bottom up through the body of the heel and consisting each of a tubular metallic pin of angular cross section, having external screw threads cut in the angular corners thereof and biting into the wood to bind the same together and to lock the pin in the position to which it is driven.

2. The combination with a one-piece wooden heel, of a pair of dowels driven from the bottom up through the body of the heel and consisting each of a metallic pin of tubular structure and of angular cross section to lock the same in the wood.

3. The combination with a one-piece wooden heel, of a pair of dowels driven from the bottom up through the body of the heel and consisting each of a metallic pin of angular cross section, having external screw threads cut in the angular corners thereof and biting into the wood to bind the same together and to lock the pin in the position to which it is driven.

4. The combination with a one-piece wooden heel, of a tubular metallic dowel of angular cross section provided with external screw threads and driven from the bottom up through the body of the heel.

In witness whereof I have hereunto set my hand this 23rd day of July, 1919.

JOSEPH BURGER.
